DEVICE FOR STRAIGHTENING AND
CURLING HAIR

Frances Bourland, Grand Prairie, Tex.

Application August 23, 1951, Serial No. 243,248

6 Claims. (Cl. 132—40)

1

This invention relates to clamps employed for holding the hair in the process of waving and it has particular reference to an improved device adapted for use both in curling and in straightening too wavy or kinky hair.

The principal object of the invention is to provide a device consisting of a pair of relatively pivoted arms, spring biased to clamping position on the hair and equipped with a clasp to hold the arms firmly in clamped relationship while the clamped lock of hair is being rolled upon a split roller, or mandrel which is subsequently brought into attaching relationship with the clamp. Moreover, the invention anticipates a tapered nib or projection split into half sections, one being formed on the upturned free end of each clamp arm and adapted, when the arms are closed, to define a spindle for reception in a correspondingly shaped recess in one end of the roller whose opposite end is received in a bifurcated ear formed on one of the clamp arms adjacent its pivoted end, thus enabling the roller to more securely hold the arms in clamping relationship while rotating the same to impose final tension on the hair.

Another object of the invention is to provide a clamp as set forth in which the tapered spindle has formed thereon a squared portion at its base which is adapted to be received in a correspondingly shaped section of the recess in the end of the roller, the latter being provided adjacent its opposite end with a squared portion receivable in the bifurcated ear on the clamp arm, such squared portions being effective to hold the roller against rotation after having been attached to the clamp.

Broadly, the invention provides a clamp and roller adapted for use in carrying out the Croquignole method, employing cold solution, both in curling as well as in removing kinks from the hair, the important characteristic of the invention residing in the specially designed features of the clamp and roller which permits the latter to be rotated while at the same time holding the clamp arms together during the final operation of tensioning the hair. Further, the provision of means for finally securing the roller against rotation on the clamp which is accomplished by shifting the roller longitudinally to bring into register the squared cavity of the roller and the squared portion of the tapered spindle as well as the squared portion of the roller and the bifurcated ear of the clamp arm.

Other objects will appear as the description proceeds, taken in connection with the accompanying drawing, wherein:

2

Figure 1 is a perspective view of a hair clamp and roller constructed according to the invention.

Figure 2 is a view of the roller *per se* partly in longitudinal section and on a larger scale.

Figure 3 is an exploded view of the clamp and roller assembly.

Figure 4 is a perspective view of the clamp *per se* shown in open position, and

Figure 5 is a sectional view taken on line 5—5 of Figure 1.

Continuing with a more detailed description of the drawing, reference numeral 10 denotes generally the clamp, made preferably of plastic and which consists of an arm 11 having an upturned end 12 and whose opposite end has an angular deflection 13 in which is formed an elongated recess 14, to which further reference will be made presently.

Adjacent the deflection 13 of arm 11 is formed a semi-circular protuberance 15 adapted to be received in the correspondingly shaped recess 16 (Fig. 3) provided in a companion arm 17 of the clamp. The arm 17 is likewise formed with an angular deflection 18 confronting the deflection 13 of arm 11, which arrangement enables the ends of the arms to be brought together when pivoted in the manner to be presently explained. The angular deflection 18 of arm 17 is also provided with an elongated recess 19.

Formed perpendicularly on the arm 17 is a bifurcated ear 20, located immediately above the recess 16 in the arm. The width of the ear 20 is equal to the combined widths of the arms 11 and 17 and one end of the ear overlies the arm 11, thus to locate the center of the square recess 21 of the ear directly over the center of the semi-circular recess 16 of the arm 17.

A hole 22 is drilled in the ear 20 perpendicular to the arm 17 and this hole registers with a hole 23 drilled in the semi-circular protuberance 15 of arm 11 when the arms are assembled and a pin 24 is passed through the holes 22 and 23 to serve as a pivot for the arms 11 and 17. It is preferred that both ends of the pivot pin 24 be countersunk, as shown in Figure 5.

A leaf spring 25 is disposed with one end in the recess 14 of arm 11 and its opposite end in recess 19 of arm 17 and exerts opposite forces on the ends of the arms tending to urge the latter into clamping position. The arms are spread apart by finger pressure exerted on the milled surfaces 26 opposite the angular deflection of each of the arms.

The clamp arm 17 has an upturned end 27 identical to the upturned end 12 of arm 11. Formed on each upturned end 12 and 27 is a

half-section 28 of a tapered protuberance, the protuberances becoming a spindle when the arms are brought together into clamping relationship. At the base of each protuberance is formed the half section 29 of a squared portion which latter serves as a means to prohibit rotation of the curling roller 30 in the manner to be presently explained.

The curling roller 30 has a center portion of reduced diameter and is provided with an elongated, transverse slot 31 opening at one end and terminating short of the opposite end of the roller in which the end of a lock of hair is received so that the lock may be wound tightly and uniformly on the roller. A cylindrical head 32 is formed on one end of the roller 30 which is recessed to define a square cavity 33 (Fig. 2) and a tapered portion 34. Spaced from the opposite end of the roller 30 is a portion 35 of the same diameter as the head 32 and, spaced toward the end of the roller from the portion 35 is a squared portion 36, the intervening space 37 being cylindrical in shape. At the extreme end of the roller is formed a handle 38 by which the roller is rotated. This handle has roughened surfaces to prevent slippage of the fingers as the roller is being manipulated.

The clamp 10 is so placed on the scalp as to engage a selected lock of hair adjacent the roots. The solution is applied to the hair and the ends thereof are placed in the slot 31 of the roller 30. The roller is rotated and the lock of hair is wound uniformly thereon until the roller is brought into juxtaposition to the clamp whereupon the roller is shifted endwise to engage its recess 34 with the tapered spindle formed by the half-sections 28. When the roller is thus disposed, the cylindrical portion 37 thereof will be in alignment with and will rest on the recess 21 of the ear 20 on the arm 17. This will hold the roller in proper relationship with the clamp while it is further rotated to impose added tension on the hair necessary to curl or straighten the hair, as the case may be.

When the desired tension is imposed on the hair, the roller 30 is further moved longitudinally to engage the squared portions 29 of the tapered spindle with the squared portion 33 of the recess in the head of the roller. When thus engaged, the squared portion 36 of the roller will be brought into engagement with the square recess 21 of the ear 20. The roller is thus held securely against further rotation while maintaining the required tension on the hair and further, the arms of the clamp are held firmly together by virtue of the engagement of the split spindle 28 by the hollow head 32 of the roller.

When the clamp is initially placed on the hair, the arms 11 and 17 are primarily held by a latch composed of a tongue 39 formed on one side of the arm 17 and having a lip a adapted to engage over a rib b formed in a recess 40 in the companion arm 11. This latch is sufficient to hold the arms together during the initial rolling of the hair but when the rolling operation is completed, the increased tension requires a more secure retaining means for the clamp arm to prevent their relative displacement. This is supplied by the cooperating squared portions of the spindle and the squared cavity in the head of the roller.

Manifestly, the construction as shown and described is capable of some modification and such modification as may be construed to fall within the scope and meaning of the appended claims

is also considered to be within the spirit and intent of the invention.

What is claimed is:

1. In a device for curling and straightening hair, a clamp comprising a pair of arms pivoted adjacent one end, each having an upturned end opposite its pivotal point, a split tapered spindle in equal half-sections, one half section being formed on one upturned end of one of said arms, the other half-section being formed on the upturned end of the companion arm, a squared portion formed at the base of each of said half-sections, an ear formed on one of said arms having a square recess disposed over the pivot of said arms, a slotted roller having a head provided with a recess having a tapered portion adapted in one position of said roller to rotatably receive said tapered spindle and a squared portion adapted to receive the squared portion of said spindle in another position of said roller to secure said arms in clamping relationship and to prohibit rotation of said roller and means on said roller engageable with the squared recess of said ear to hold said roller against rotative and lateral displacement with respect to said clamp.

2. A hair clamp and roller comprising a pair of relatively pivoted arms normally spring biased to closed position, an upturned end on each of said arms opposite their pivotal point, a protuberance formed on each of said upturned ends, said protuberances jointly forming a tapered spindle in closed position of said arms, a roller having a head provided with a recess combining a squared portion and a tapered portion adapted in one position of said roller to rotatably receive said tapered spindle to hold said arms in closed position, a squared portion formed at the base of each of said protuberances, said squared portions adapted to be jointly received by the squared portion of the recess of said head in another position of said roller to hold the latter against rotation and means adjacent the pivotal point of said arms for receiving the opposite end of said roller.

3. A hair clamp and roller comprising a pair of arms pivoted together adjacent one end and normally spring biased into relative parallelism, an upturned end on each of said arms opposite their pivotal point, a protuberance on each of said upturned ends, said protuberances jointly defining a tapered spindle when said arms are in closed position, an ear formed on one of said arms having a portion overlying the other of said arms and provided with a squared recess in alignment with the pivotal point of said arms, a hair roller having a recessed head receiving said spindle and provided with a cylindrical portion disposable in the recess of said ear in one position of said roller to hold said roller rotatably in relation to said clamp and means operative in another position of said roller to hold the same against rotation with respect to said clamp.

4. A hair clamp and roller comprising a pair of pivotally connected arms movable into relative parallelism, each having an upturned free end, a protuberance on each of said upturned ends, said protuberances jointly defining a tapered spindle in closed position of said arms, a squared portion at the base of each of said protuberances, an ear formed on one of said arms at the pivotal point thereof having a recess, a hair roller having a cylindrical portion and a recessed head respectively engageable with

the recess of said ear and said tapered spindle in one position of said roller to respectively secure said arms in closed position and to hold said roller rotatably in relation to said clamp and means formed jointly on said clamp and said roller to hold the latter against rotation with respect to said clamp.

5. The structure of claim 4, in which the ends of said arms next adjacent to their pivotal point are angularly deflected, the confronting deflected surfaces each being recessed, and a leaf spring of substantially V-shape having its ends lying

10

in said recesses to normally urge said arms into relative parallelism.

6. The structure of claim 4, in which the means for holding the roller against rotation consists of a squared portion formed on said spindle adjacent its base receivable by a squared portion in the recess in the head of said roller and a squared portion on said roller receivable by the recess in said ear.
